UNITED STATES PATENT OFFICE

ARTHUR E. MODINE, OF RACINE, WISCONSIN, ASSIGNEE TO MODINE MANUFACTURING COMPANY, OF RACINE, WISCONSIN, A CORPORATION OF WISCONSIN

HEATING UNIT

Application filed May 28, 1926. Serial No. 112,376.

My invention relates to heating systems and particularly to radiators and means controlling the operation of the radiators.

The invention has among its other objects the production of apparatus of the kind described which is compact, convenient, durable, efficient and of simplified construction.

A particular object of the invention is to provide improved means for controlling the flow of air around or through a radiator core.

One form of the invention is embodied in a radiator comprising a housing in the lower end of which a radiator core is disposed, the arrangement being such that air may enter the lower end of the housing and pass out the upper end thereof. The operation of the radiator is controlled by means of an adjustable damper which controls the flow of air through the housing, the damper preferably comprising a pivoted plate which is connected by worm gearing to a handle or knob to permit adjustment of the damper.

Another form of the invention is embodied in a radiator of substantially the same construction as the radiator described above, the pivoted damper being replaced by a damper comprising a rolled partition which may be unrolled to regulate the flow of air through the radiator.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a vertical section taken through heating apparatus embodying the invention;

Fig. 2 is an enlarged plan section taken on line 2-2 of Fig. 1;

Fig. 3 is a section taken on line 3-3 of Fig. 2; and

Fig. 4 is a fragmentary section taken through apparatus embodying another form of the invention.

Referring for the present to Figs. 1 to 3, inclusive, wherein I have illustrated one form of the invention embodied in a radiator device adapted to be positioned in a room or the like, the reference character 10 designates generally a housing supported by a plurality of legs 11 in such manner that air may enter the lower end of the housing and pass through a radiator core 12, the heated air being discharged through an opening 14 in the upper end of the housing. As shown, a grille or screen 15 is preferably disposed in the opening 14, and a curved air deflecting member 50 is provided in the upper part of the housing for deflecting air outwardly through the grille 15. My invention is limited to the use of a housing only to the extent indicated in the appended claims as it will become apparent as this description progresses that the core 12 could be mounted in any suitable passage such as, for instance, a passage formed in a wall or the like.

The radiator core is preferably of the type more fully shown and described in my co-pending application Serial No. 112,376 filed May 28, 1926, which has now matured into Patent No. 1,677,457 granted July 17, 1928, and in this instance comprises a plurality of spaced tanks 16 and 17 which communicate with each other through a plurality of thin walled tubes 18 provided with transversely arranged fins 19. Merely for the purposes of this disclosure, I have illustrated the radiator core 12 as part of a hot water system, the means for connecting the radiator core to the hot water system preferably comprising pipes 20 and 21 which communicate with the tanks 16 and 17, respectively, by means more fully shown and described in the aforementioned patent wherein I have also disclosed that the radiator core is preferably supported by the pipes.

Means for controlling the flow of air through the housing 10 comprises a damper 25 which in this instance is formed of a sheet metal plate secured along one edge to a shaft 27 which has its ends journaled in bearing members 29 and 30 rigidly secured to the tanks 16 and 17, respectively. Rigidly secured to the shaft 27 intermediate its ends 32

is a worm gear 32, the damper 25 being preferably cut away as at 33 to provide space for the worm gear. Meshing with the worm gear 32 is a worm 34 rigidly secured to a rod or shaft 35 rotatably journaled in bearing members 36 and 37. The bearing member 36 is preferably a bracket mounted upon the radiator core 12 and, in this instance, the bearing member 37 is formed of a flat bar of metal 5 also mounted upon the radiator core. The shaft 35 preferably extends through an aperture 38 formed in the housing 10 and is preferably provided with a hand-wheel or knob 39 whereby the shaft may be rotated so that 10 the worm 34 will rotate the worm gear 32. Obviously, rotation of the worm gear 32 will result in angular displacement of the damper 25 around the longitudinal axis of the shaft 27. It will be noted that the damper 25 may 15 be brought into a position wherein it substantially prevents a flow of air through the radiator core 12 and that it may be brought into a plurality of adjusted positions to control the volume of air passing through the core. 20 When the above described apparatus is in operation, and hot water is passing through the tubes 18 a column of air flows through the housing 10, the air entering the open lower end of the housing and being discharged 25 through the opening 14. Of course, if the damper 25 has been brought into the position wherein it is shown in full lines in Fig. 3, there will be no appreciable flow of air through the radiator core and there will not 30 be an efficient exchange of heat between the hot water and the air surrounding the tubes. Thus, an attendant may bring the damper 25 into position wherein it is shown in full lines 35 in Fig. 3 when the temperature of the room 40 is too high, or the attendant may adjust the damper 25 so that a predetermined temperature may be maintained within reasonable limits. If the room is cold, the damper 25 is preferably brought to its fully opened position 45 so that a maximum amount of air will pass through the radiator core and the radiator core will function with maximum efficiency.

In Fig. 4 I have illustrated another form 50 of the invention embodied in heating apparatus which preferably comprises a radiator core 40 which is substantially identical in construction with the aforementioned radiator core 12. For the purposes of this disclosure the radiator core 40 is mounted in a housing 41 which may be considered to be substantially identical in construction with the aforementioned housing 10. Journaled above the radiator core 40 is a roller 42 which 55 is preferably of the Hartshorn type and preferably comprises a spring (not shown) which tends to wind a curtain or collapsible partition 44 around the roller. The roller 42 is 60 preferably mounted upon brackets carried by 65 the radiator core, one of these brackets being

shown at 45. Secured to one end of the collapsible partition 44 is a cable 47, or the equivalent, which extends through an aperture 48 formed in the housing 41 and is provided with a knob 49, or the equivalent, at its outer end. Obviously, the collapsible partition 44 may be unrolled from the roller 42 by pulling upon the knob 49, the construction being such that any desired portion of the collapsible partition 44 may be unrolled to 70 regulate the amount of air passing through the radiator core. The collapsible partition 44 functions substantially in the same manner as the aforementioned damper 25 and may be employed to regulate the temperature of a 75 room in which the radiator core 40 is placed. 80

The collapsible partition 44 may be made of any suitable material which is sufficiently flexible to permit its being rolled upon the roller 42. In some instances, I prefer to form 85 the collapsible partition 44 from a plurality of strips of metal which are pivoted to each other.

Having thus described by invention, it is 90 obvious that various immaterial modifications may be made in the same without departing from the spirit of my invention; hence I do not wish to be understood as limiting myself to the exact form, construction, arrangement and combination of parts herein 95 shown and described or uses mentioned.

What I claim as new and desire to secure by Letters Patent is:

1. In a heating system, a radiator housing having openings in its upper and lower ends, a radiator core disposed within the housing, a shaft, means mounted upon the radiator core for rotatably journaling the shaft, a damper secured to the shaft, a worm gear secured to the shaft, a worm meshing with said gear, and means projecting through the housing for rotating the worm. 100

2. In a radiator, the combination of a radiator core, a casing in which said core is mounted, a damper located in said casing adjacent said core, said damper being pivotally connected with and arranged at one edge of the core and tending to move by gravity in one direction, means arranged at 105 said edge of the damper for angularly adjusting said damper relatively to said core and holding said damper in one of several positions of angularity, said means including a member fixed for rotation with said damper, and a rotatable member extending beyond the casing having means which rotatably engages with said member of the damper, said means of said damper and the means of the rotatable member cooperating with each other to hold said damper in adjusted position. 110

3. In a radiator, the combination of a radiator core, a damper pivotally connected with the core adjacent an edge of the core and tending to close by gravity, and means lo- 115 120 125

cated at said edge for angularly adjusting and holding said damper in various positions of angularity relatively to said core.

4. In a radiator, the combination of a radiator core, a casing in which the core is located, said casing having an outlet opening above the core, a damper arranged for movement in said casing, said damper being pivotally connected adjacent an edge with the 10 core and tending to close by gravity, and means located at said edge and connected with the core for angularly adjusting and holding said damper in various positions of angularity relatively to said core, said means 15 including elements rotatably engaging each other, one of said elements providing means for rotating and resisting rotation of the other to thereby move said damper and hold said damper in adjusted position.

20 5. In a radiator, the combination of a radiator core, a casing in which said core is located, a damper arranged for movement in said casing adjacent the core, a shaft providing a pivot for said damper, a shaft arranged transversely of said damper shaft 25 extending beyond the casing and providing an element of means for adjusting said damper, said shafts each being provided with rotatable members which are fixed relatively 30 to said shafts and rotatably engage each other, one of said members providing means for rotating the other and providing means resisting rotation thereof, said shafts and rotatable members carried thereby being 35 united with the radiator core for support thereby.

6. In a radiator, the combination of a radiator core, a casing, a damper, and means for moving the damper relatively to said core, 40 said core being located in one end of said casing, said damper and means being arranged adjacent said end of the casing and including a shaft arranged transversely of said casing and damper and rotatably engaging elements respectively secured to said shaft and damper and united with the core for support by the core.

45 7. In a radiator, the combination of a radiator core, a casing, a damper rotatably secured to the core and normally tending to move in one direction relatively to the core, and means for controlling movement and moving said damper relatively to the core, said means being supported by the core and 50 including transversely arranged rotatably engaging elements and a member to which one of said elements is connected, said member being extended beyond said casing.

55 8. In a radiator, the combination of a casing, a radiator core, a damper secured to the core, and means including a shaft providing a pivot for said damper and a shaft arranged transversely to said first mentioned shaft, each of said shafts having means rotatably engaging each other and fixed for

rotation with said shafts, one of said means providing means for rotating and holding the other against rotation to thereby move said damper and hold said damper in various angular positions relatively to said core. 70

9. The combination with a housing, of a radiator core disposed within the housing, a damper disposed within the housing and connected with the core for controlling the flow of air therethrough, and means including a plurality of gears for displacing the damper, and means in said housing for deflecting a current of air outwardly therefrom into a room. 75

10. In a heating system, a radiator housing having an opening at its lower end and having an opening at its upper end on one side thereof, a radiator core positioned in the lower end of said housing, a pivoted damper disposed within the housing and supported by the core, rotatable means for adjusting the damper, said means providing means for holding the damper in several positions of angularity relatively to the radiator core. 80

In testimony whereof, I have hereunto signed my name.

ARTHUR B. MODINE.
